(57) **CLAIM**

We claim the ornamental design for the water bottle, as shown and described.

DESCRIPTION

FIG. 1 is a first perspective view of a water bottle showing our new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is a top perspective exploded view thereof.

The broken lines in the figures illustrate portions of the water bottle that form no part of the claimed design.

1 Claim, 8 Drawing Sheets
